The ornamental design for a display stand for tablet with deformable rest pad, as shown and described.

DESCRIPTION

FIG. 1 is a top plan view to of the display stand for tablet with deformable rest pad showing my design;

FIG. 2 is a bottom plan view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a front perspective view thereof shown supporting a tablet;

FIG. 8 is a front elevational view thereof showing the rest pad on uneven surfaces;

FIG. 9 is a rear elevational view thereof showing the rest pad on uneven surfaces;

FIG. 10 is a left elevational view thereof showing the rest pad on uneven surfaces; and,

FIG. 11 is a right elevational view thereof showing the rest pad on uneven surfaces.

The broken lines in the FIGS. 7-11 are for illustration purposes only and form no part of the claimed design.
